UNITED STATES PATENT OFFICE.

NEWTON C. SCHELLENGER, OF ELKHART, INDIANA, ASSIGNOR TO CHICAGO TELEPHONE SUPPLY COMPANY, OF ELKHART, INDIANA, A CORPORATION OF DELAWARE.

JACK.

Application filed February 21, 1925. Serial No. 10,726.

My invention relates to jacks for telephony, radio, and the like.

While the jack of my invention is particularly adapted for a connecting member on the end of a cord or the like, commonly called a mounted jack, it is to be understood that the invention is not limited to an individually or separately housed jack, but may be applied generally to jacks mounted on panels, switchboards, or in strips, or the like.

According to the preferred form of my invention I provide two generally parallel springs which are connected at their front ends to a common thimble or body member, this may be a strip panel or the like, if desired, and at their rear ends they are connected together for the dual purpose of increasing the strength of the springs and for supporting suitable terminals. The plug which is inserted through the thimble, panel, strip, or the like, is engaged by intermediate portions of these springs which intermediate portions are bent down to co-operate with the tip and sleeve portions of the plug. If more than two contacts, i. e., tip and sleeve, are desired, that is for example, if a ring contact is to be employed on the plug, an additional spring may be mounted in a similar manner and connected at its front to the body, panel, strip, or the like, and at its rear to the connecting member, or it may be free at its front end and mounted upon the connecting block or frame at its rear only. In fact, in one form of my invention disclosed herein the springs may all be free at their front ends and secured to the block or frame at their rear only. Where the jack is separately mounted, a protecting sleeve or housing of insulating material is mounted on the thimble and it provides an opening through which the conductors connected to the springs may project.

I find that with the use of springs connected at both ends and employing only the contacting intermediate portions a very light spring is permissible, and yet excellent contact and relatively high contact pressure may be employed. Preferably the connecting member between the rear end of the springs

is a block of insulating material to which the springs are connected, so that the spring structure really forms a truss within itself. This may be varied by employing a hollow member like a ring or sleeve of insulation. The terminals may be formed either as continuations endwise or sidewise of the point of attachment to the block, or the means which attach the ends of the springs to the block may serve also as terminal means.

I have shown in the accompanying drawings a number of ways in which my invention may be embodied in order that those skilled in the art may be advised how to construct and operate an embodiment of my invention.

In the drawings: Figure 1 is a longitudinal section showing the spring structure in elevation of an embodiment of my invention;

Fig. 2 is an axial longitudinal section taken at right angles to the view of Fig. 1;

Fig. 3 is a view like Fig. 2 of a modification;

Fig. 3^A is a cross section of a modification of Fig. 3 showing a different way of attaching the front ends of the springs;

Fig. 4 is a transverse section taken on the line 4—4 of Fig. 3;

Fig. 5 is a transverse section like Fig. 4 showing a modification of the manner of connecting the outer ends of the springs together;

Fig. 6 is a similar view of a further modification;

Fig. 7 is an exploded view of a modified form of jack in which the springs are connected together at their front ends by a sheet metal thimble or hollow rivet, so that the jack may be mounted upon a panel by means of the usual jack thimble and nut;

Fig. 8 is a top plan view of a modified form of jack embodying my invention;

Fig. 9 is a vertical axial section of the device shown in Fig. 8;

Fig. 10 is a similar section of a modification;

Fig. 11 is a transverse section taken on the line 11—11 of Fig. 9;

Fig. 12 is a longitudinal section of a modi-

fied form of jack in which a sleeve of insulation is employed for mounting the jack springs;

Fig. 13 is a cross section of the same taken 5 on line 13—13 of Fig. 12;

Fig. 14 is a top plan view of the sleeve and springs employed in the structure of Figs. 12 and 13;

Fig. 15 is a longitudinal section of a modified form of mounted jack in which the jack springs are mounted upon a connecting member which is held inside the mounting shell by a pair of braces or strips; and

Fig. 16 is a cross section of the device shown 15 in Fig. 15, line 16—16.

As shown in Figs. 1 and 2, the mounted jack 1 is connected at the end of the flexible conducting cord 2 and is adapted to co-operate with the plug member 3. The plug comprises a stud having two electrical contacts, namely, the sleeve member 4 and the tip member 5, the construction of which is well known to those skilled in the art. The jack member 1 comprises a metallic thimble 6, shown in Figs. 1 and 2, having a knurled portion 7 and a threaded portion 8 by which the sleeve or shell 9 may conveniently be secured to said thimble member 6. The thimble 6 has a reduced neck 10 extending rearwardly thereof and upon this neck are mounted the eye portions of the two springs 11 and 12. These eye portions are bent at right angles to the main parts of the springs 11 and 12 and embrace the neck 10 of the thimble 6. The spring 11 is grounded upon this neck 10 and the eye of the spring 12 is insulated therefrom by insulating washers 13 upon each side thereof and an insulating ring 14 lying radially between the edge of the eye and the surface of the neck or sleeve 10. The end of the neck or sleeve 10 is seated over the adjacent washer 13 to form a suitable head, the parts being then held together by friction. The springs 11 and 12 have bent portions or humps 15 and 16, respectively, for engaging the sleeve and tip contacts 4 and 5, respectively, of the stud portion of the plug. At their rear ends just beyond the end of the plug, the springs 11 and 12 are tied together by a connecting member 17, in this case a block of insulating material which holds the springs 11 and 12 definitely at the right distance apart and prevents spreading of the outer ends of the same. The springs 11 and 12 have perforations 55 through which are passed the hollow rivets 18 and 19, these rivets being headed over as indicated in Fig. 2 to secure the block 17 firmly to the springs 11 and 12. The inner ends of these hollow rivets are inserted in the interior of the block 17. If desired, screws may be threaded into the block 17 in place of the rivets 18 and 19.

In the form shown in Figs. 1 and 2 the springs 11 and 12 extend rearwardly and are 65 doubled upon themselves to form terminal

portions 20, suitable clamping screws 21 being provided for clamping the tips of the conductors 22 and 23 of the cord 2. If desired, the bolts 21 may be passed loosely through the springs 11 and 12 and may be held by nuts 70 lying on the inside of these springs 11 and 12.

In the embodiment shown in Figs. 3 and 4, the springs 24 and 25 corresponding to the springs 11 and 12 are connected at their front ends by the rivets 26 and 27, which are embedded in the thimble member 28, which in this case is made of insulating material. Screws may be employed instead of the rivets 26 and 27 and if desired the springs 24 and 25 at their forward ends may have lateral expansion as indicated at Fig. 3^A, so that rivets or screws 29 and 30 may be secured at the sides of the springs 24 and 25 instead of directly between them, as illustrated in Fig. 3.

In the form shown in Figs. 3 and 4 the springs 24 and 25 are connected to the block 17 at their rear ends, the springs terminating at said block and separate angular clips 31 being riveted to said springs through the rivets 32 embedded in the block 17, so that in effect the springs extend off laterally. These angular clips 31 are provided at their outer ends with clamping screws 33 for clamping the terminals of the flexible conductor 2.

Instead of having the separate angle pieces 31 the springs themselves may have laterally extending ears, as shown at 34 in Fig. 6, suitable terminal screws 35 passing through these ears and into the block 36, this block 36 corresponding to the connecting member 17 in the foregoing figure.

In this construction the screws 35 are offset with respect to each other so that they may be made amply long to secure a good hold on the block 36 and also to serve as clamping means for the terminals of the connecting conductors.

In Fig. 5 I have shown the outer ends of the springs 24 and 25 as carried on the inside of a ring 26 of insulating material, preferably a piece of fiber tubing, suitable clamping screws 38 and 39 passing through the ring 37 and into the springs 24 and being adapted to clamp, either between the springs and the ring 37 or under the heads of the screws 38, the terminals of the conductors to which the springs are connected.

In Fig. 7 I have shown the springs 11 and 12 such as shown in Fig. 1 as connected together by a sheet metal thimble 40 so as to hold the front ends of these springs together in insulated relation for mounting of the jack upon a panel or the like. The eye ends at the forward parts of the springs 11 and 12 are separated by a suitable insulating washer 41 and are held out of contact with the metal thimble 40 by a sleeve 42 and outer washers 43. The usual jack thimble 44 is passed through the sheet metal thimble or hollow rivet 40 and is adapted to co-operate with the 130

nut 45, so that the jack of Fig. 7 may be mounted upon a switchboard panel, or the like.

In Figs. 8 and 9 I have shown a modification in which the main springs 46 and 47 have outwardly turned foot portions 48 and 49 riveted by means of the hollow rivets 50 to a ring of insulating material 51 which lies upon the back side of the panel board 52 and 10 is clamped by means of the usual threaded thimble 53.

At the rear end the springs 46 and 47 are connected to a common connecting member 54 as by means of the pairs of rivets 55 and 15 56, these rivets holding also co-operating contact springs 57 and 58 in insulated relation upon the block 54, so that insertion of the plug 3, in addition to making contact with the springs 46 and 47, closes contact between 20 springs 46 and 57 and 47 and 58, respectively. Obviously the contacts may be opened instead of closed as indicated, for example, in Fig. 10. Any combination of opening and closing may be made in a usual and well known manner. In the structure of Fig. 10 the springs 25 46 and 47 have co-operating contact springs 57' and 58' lying between them and the circuits between springs 46 and 47 and between the springs 47 and 58 are opened by the insertion of the plug member 3. Otherwise the construction and mode of operation is the same as shown in Fig. 9.

In the modification shown in Figs. 12, 13 and 14, I employ a sleeve of insulating material 60 upon which the springs 61 and 62 are mounted, these springs having contact portions 63 and 64 extending inwardly and being attached at their forward and at their rear positions inside of the sleeve 60, as by 40 means of the rivet 65. At their rear the springs 61 and 62 have extensions beyond the point of attachment to the sleeve 60 for forming terminal portions 66 and 67, these terminal portions having suitable clamping screws 45 68 and 69 for clamping the conductors of a cord, or the like.

This sleeve of insulating material 60, with the springs 61 and 62 and their terminals suitably mounted as a unit, is inserted inside 50 of an outer shell of insulation 70 which is threaded at its forward end to the thimble 71, this thimble being provided with a suitable aperture 72 for receiving the plug. The rear end of the shell 70 has an inwardly extending flange 73 having an aperture 74 to admit the conductors which are connected to the terminals 66 and 67. The sleeve member 60 is of such a length as to be secured firmly 55 between the thimble 71 and the inturned flange 73 when the shell 70 is threaded upon said thimble 71.

The operation of this embodiment will be apparent from the foregoing description. The jack is inserted in the opening 72 and 65 the contact portions of the jack engage the

humps 63 and 64 and make firm contact with the same.

The sleeve 60 of insulating material may be cut out intermediate the ends of the springs 61 and 62, if desired, as shown in the 70 drawings, but this is optional. Preferably, the sleeve 60 fits snugly in the shell 70.

In the embodiment shown in Figures 15 and 16, the jack comprises a pair of springs 75 75 and 76 which are connected at their rear ends by means of the connecting member 77, which in this case is a block of insulating material. The rear ends of the springs are preferably secured to this block as by means of the screws 78. Lateral extensions of the 80 ends of the springs bear the contact springs 79 for connecting to the conductors of a cord, or the like. The clamping screws 79 are preferably placed back of the clamping screws 78 so as to give two points of attachment for the springs to the block 77 to strengthen the connection between the springs and the block. The rear ends of the springs 75 and 76 are offset with respect to each other as is clear from Fig. 16, so that 85 the screws 78 and 79 may take firm hold in the block 77 without danger of short circuiting the connection.

The block 77 is mounted inside of the shell 80 by means of two strips or braces 81 and 95 82 which in turn are fastened to the edges of the block 77, as by means of suitable screws. These braces or strips 81 and 82 are of a length such as to fit nicely between the flange 83 at the rear end of the shell 80 and the 100 thimble 84 to which the front end of the shell 80 is threaded.

I do not intend to be limited to the details shown or described.

I claim:

1. In a jack of the character described, the combination of a body having an opening therein, a pair of springs secured at their forward ends to said body and having terminal portions at the rear, and a rigid insulating member to which the rear of said springs are attached for maintaining spaced relation between said springs.

2. In a jack, a body having an opening for guiding a plug member; a pair of springs 115 connected to said body at their forward ends, said springs being bent in their intermediate portion to engage the contacts of a plug, and an insulating member to which said springs are attached at their rear ends for maintaining spaced relations between said springs.

3. In a jack, a tubular member adapted to receive a plug, a pair of spaced springs extending outwardly from said member, being firmly connected at one end to said member, a rigid insulating member to which the other end of said springs are attached for holding said other ends in spaced relation, and a shell connected to said tubular member for enclosing said springs, said springs having interme- 125 130

diate portions adapted to be engaged by the contacts of a cooperating plug.

4. In a jack of the character described, a pair of contact springs insulated from each other and secured at their front and rear ends in fixed relationship with respect to one another, said springs extending longitudinally from the front to the rear of the jack

and being bent intermediate of their ends, and a body member having an opening for 10 guiding a plug member to connect with the bent portion of said springs.

In witness whereof, I hereunto subscribe my name this 18th day of February, 1925.

NEWTON C. SCHELLENGER.
